UNITED STATES PATENT OFFICE.

HARRY C. KETTELSON, OF MILWAUKEE, WISCONSIN, ASSIGNOR OF ONE-HALF TO
WILLIAM H. LAWTON, OF MILWAUKEE, WISCONSIN.

ROOFING-CLEAT.

1,187,532.

Specification of Letters Patent. Patented June 20, 1916.

Application filed March 20, 1916. Serial No. 85,282.

To all whom it may concern:

Be it known that I, HARRY C. KETTELSON, a citizen of the United States, and resident of Milwaukee, in the county of Milwaukee and State of Wisconsin, have invented certain new and useful Improvements in Roofing-Cleats; and I do hereby declare that the following is a full, clear, and exact description thereof.

10 The present invention relates to new and useful improvements in metallic cleats particularly adapted for securing roofing sheets to the roof boards of buildings and for use in other connections wherein the cleats 15 would be exposed to the weather.

Various types of cleats adapted each to receive a plurality of nails for procuring a clamping action on the roofing sheets, have been heretofore provided but these cleats 20 have been open to serious objection in that a rusting of the nails is permitted. Practice demonstrates that the roofing sheets will operatively outlast two or three sets of nails in connection with the usual cleats and it 25 has been found that water in accumulating in the rib of the cleats procures an excessive rusting of the nails.

It is therefore an important object of the present invention to provide roofing cleats 30 wherein the nails may be efficiently protected against access of water to their portions within the cleats.

Roofing sheets are generally employed in connection with more or less temporary 35 building structures and thus in practice an unevenness of the surface over which the roofing sheets are laid would often be encountered.

It is therefore a further object of the invention to provide a roofing cleat so formed and braced as to procure a positive clamping action only between pairs of adjacent nail receiving portions, whereby each pair of adjacent nails define an independent clamping 40 portion to thus provide compensation for slight unevenness of the surface on which the cleat is secured, and further so that if desired the cleat may be bent adjacent respective nail receiving portions to extend 45 around a corner.

With the above and other objects and advantages in view, the invention resides more particularly in the novel combination, arrangement and formation of parts more par-

ticularly hereinafter described and particularly pointed out in the appended claims. 55

In the drawings: Figure 1 is a plan view of the roofing cleat constructed in accordance with the present invention. Fig. 2 is a central longitudinal sectional view therethrough, as indicated by the line 2—2 of Fig. 1. Fig. 3 is a transverse sectional view through one of the nail receiving portions of the cleat on the line 3—3 of Fig. 1. Fig. 4 is a transverse sectional view through one of 60 the clamping portions of the cleat on the line 4—4 of Fig. 1. Fig. 5 is a sectional view taken transversely through a modified form of nail receiving portion.

Referring now more particularly to the accompanying drawings, the cleat comprises a flat body plate 5, and struck upwardly at longitudinal points along the plate are cup shaped projections 6 centrally apertured at 7 to receive a securing nail. In the drawings only three of these cup shaped nail receiving portions are shown although it is apparent that any desired number could be employed in connection with a single cleat. Disposed between each pair of nail receiving portions is a longitudinal rib 8 which has its ends preferably rounded and terminating adjacent the bases of the respective nail receiving portions, this rib being shown as longitudinally fluted although it may comprise merely a single arched cross section. The diameters of the nail receiving cups 6 are but slightly less than the width of the plate, and thus between the cups and the edges of the plate, and between the cups 90 and the ribs a narrow clamping surface is provided whereby upon driving a nail through the cup into the roofing board a positive clamping edge will be procured to effectively seal the interior of the nail cup 95 against access of water, whereby the nail is prevented from rusting.

Fig. 3 shows, in connection with a cross section of the cleat through a nail receiving portion, overlapping ends 9 of respective 100 roofing sheets and a nail 10 is passed through the cleat portion and into a roofing board 11.

The cleat plate between the brace ribs and the sides of the nail cups is not braced and consequently may be readily bent. Thus 105 each pair of nails procures a somewhat independent clamping action of the rib disposed therebetween, and thus the ribs may

assume differing relative positions within a certain restricted limit to compensate for slight variations in the surface to which the cleats would be applied, also by the foregoing structure the cleats may be bent at either side of a nail cup to extend around a corner, this bending being procurable without detracting from the clamping action of any portion of the cleat, and it is noticed that if 5 the cleat were provided with a longitudinal brace structure throughout, such bending could not be procured without a consequent bowing of adjacent portions which would interfere with the clamping action.

10 In Fig. 5 is shown a modified form of cleat wherein the arched cross section of a plate 12 is shown and may comprise either a cup portion 6 of the plate or may comprise part of a longitudinal rib, this arched portion 15 is provided with a center opening 13 for receiving the nail 14, and the material at the sides of the opening is bent downwardly to form a nail receiving sleeve 15, the free end of which sleeve is extended 20 past the body of the plate and thus in operation bites into the roofing sheet, as shown and forms an effective seal against access of water to the nail.

25

Copies of this patent may be obtained for five cents each, by addressing the "Commissioner of Patents, Washington, D. C."

I claim:

1. A roofing cleat comprising a flat body 30 plate provided at longitudinally spaced intervals with outwardly struck nail receiving cup portions and with outwardly struck ribs each disposed between a respective pair of cup portions and terminating short of said 35 cup portions to permit transverse flexure of the plate at the sides of the cups.

2. A cleat of the type described comprising a flat body plate provided at longitudinally spaced intervals with nail receiving 40 cup portions having their diameters slightly less than the width of the plate to procure a clamping edge in connection with the sides of the plate, and a rib extending between 45 each pair of respective cup portions and terminating adjacent the bases of said cup portions.

In testimony that I claim the foregoing I have hereunto set my hand at Milwaukee, in the county of Milwaukee and State of 50 Wisconsin, in the presence of two witnesses.

HARRY C. KETTELSON.
